UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO.

SALES-CHECK HOLDER.

Application filed November 3, 1922. Serial No. 598,700.

This invention is an improvement in sales check holders and with respect to its more specific features to combined holders and punches.

5 An object of the invention is to provide a simple and inexpensive device of the class described combining in a single article, the functions of a holder for the checks, and a means to operate upon the checks to indicate 10 the charge.

Another object is to provide a device adapted to be held in the hand, and having the cutting means so arranged that it may be operated by the hand which grasps the 15 device.

Another object is to provide a device wherein the check may be detached from the holder and marked to indicate the charge, without reversing the position of the 20 device or the check.

Another object is to provide a device, wherein the figures on the check are visible throughout the cutting operation, and wherein the holder may be used in normal 25 or reversed position.

Another object is to provide a construction of cutter or punch operating to shear from the check a piece having a selected pattern.

Other objects will be in part obvious and 30 in part pointed out hereinafter.

The invention accordingly consists in the features of construction, combinations of elements and arrangement of parts which will be exemplified in the construction herein- 35 after set forth, and the scope of the application of which will be indicated in the following claims.

In the accompanying drawings similar reference characters refer to similar parts throughout the several views.

40 Figure 1 is a perspective view of the improved holder in use.

Fig. 2 is a bottom plan view showing another method of cutting the check,

Fig. 3 is an edge view.

In the present embodiment of the invention, the holder comprises a pad supporting plate 1 of suitable material, as for instance sheet metal, having at one face means to 45 clamp a pad of blank checks 2 to the holder.

The said means is in the form of an overlying arm 3 connected to the adjacent end of the plate by an integral connection 4, and the free edge of the arm is beaded as indi-

cated at 5, the bead being on the under face 55 of the arm. The bead engages the pad of checks, at the connected ends thereof, and clamps them to the plate.

The plate 1 is of greater length than the length of the pad, and at the end remote 60 from the clamping means for the pad, the plate extends beyond the pad. At the said end the plate has a V shaped notch or punch opening 6, the notch being an isosceles triangle arranged with its base toward the 65 pad of checks, and with its apex outward. A blade or strip of resilient metal 7 is secured to the plate 1 intermediate its ends. In mounting this strip or blade 7, the plate 1 is provided with a transverse slot 12 70 through which the strip 7 may be inserted so that opposite ends are disposed above and below the plate respectively. The securing of the strip to the plate 1 may be accomplished in any suitable manner, such for 75 example as riveting. In order to provide for the marking of the checks, the portion 8 of the strip or blade 7 located below the plate is converted into a punching jaw by shaping the end 8 for projection through the 80 punch opening 6. This portion 8 of the blade is bent at an angle to the body thereof, as shown, toward the plate 1, so that when the blade is pressed toward the plate, the end 8 will pass through the notch 6, and the 85 point of the end 8 will extend beyond that face of the plate upon which the blanks are arranged. The edges of the end or punch 90 8 of the blade are beveled or sharpened to form cutting edges, and the said edges co-operate with the sides of the notch as ledger blades, to remove a portion of the check, having a selected pattern, in the present instance a triangular or V shape.

In order that the figures on the check may 95 be visible during the marking of the check, the extended portion of the plate is provided with a relatively large peep opening 9 outside of the notch 6. The long axis of the opening 9 extends transversely of the plate, 100 and the opening is of a length to clearly show one of the sets of numerals, representing amounts on the check, when the check is properly placed with respect to the cutter. In order to position the check properly with 105 respect to the cutter or punch, the plate 1 has struck-up lugs or check arresting stops 10 at opposite sides of the notch 6, and these

lugs are adapted to be engaged by the edge of the check when it is positioned to display the numerals through the peep opening 9. When the check is properly positioned, that set of numerals at which it is desired to mark the check is within the opening 9, and clearly visible. That wall of the opening 9 adjacent to the notch 6 has an inwardly extending pointer or indicator 11, which indicates the position of the punch and the proper position for that set of numerals, adjacent to which it is desired to cut or punch the check. The portion of the blade 7 or the punching jaw disposed below the plate 1 is inclined downwardly from the plate toward its free end as shown in Fig. 2, so that a check may be inserted between the plate and jaw. When the blade or jaw is pressed toward the plate, the apex of the end or punch 8 first engages the check and punches a hole, after which the side edges of the end 8 sever the piece to be removed along diverging lines with a shearing cut.

In the use of the improved device, it is held as shown in Fig. 1, in the left hand, with the printed faces of the checks upward. When now it is desired to mark a check, the check is torn away from the pad by the right hand, and without any change in the position of the holder, and without reversing the check, the check is placed beneath the extended end of the plate, against the guide lugs 10 displaying the numerals through the peep opening. The check is moved longitudinally to bring the required set of numerals in line with the indicator 11, and merely by tightening the grasp on the holder the cutter or punch is operated to positively remove a portion having a selected pattern from the body of the check. If it is desired, the holder may be reversed as shown in Fig. 3. In this position the check is placed on that face of the plate adjacent to the user, against the guide lugs 10, and with the set of numerals which it is desired to mark, in line with the blade 7. Pressure on the blade will remove a portion of the check in the same manner as above described. The configuration of the end 8 may be changed if desired, to provide any desired pattern. The end 13 of the blade which is disposed above the plate adjacent to the clamping means for the pad inclines away from the plate, and provides means to cooperate with the clamping arm 3 to firmly grip the pad. When a pad is exhausted, the stubs are removed, and a new pad is inserted, by pushing it longitudinally of the plate, between the same and the clamping arm. The check holder and marker may be cut or stamped from sheet metal, and for this reason may be very cheaply manufactured. The device as a whole is light, and requires no particular exertion to operate. It may be, if desired, provided with a ring, a swiveled ring, or any other desired form of attaching

means, for attaching the device to a belt for instance.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. A holder for a pad of checks including, in combination, a pad supporting plate having a punch opening, and a strip of resilient metal held on the plate intermediate its ends, the opposite ends of said strip lying opposite opposite faces of said plate respectively, one of said ends having a punching jaw adapted to cooperate with the punch opening to mark a check in position between the punching jaw and plate and the other end providing a spring cooperative to retain the pad on the holder.

2. A holder for a pad of checks including, in combination, a pad supporting plate having a punch opening, said plate having a peep-opening at a point outside said pad, and a strip of resilient metal held on the plate intermediate its ends, the opposite ends of said strip lying opposite opposite faces of the plate respectively, one of said ends having a punching jaw adapted to cooperate with the punch opening to mark a check in position between the punching jaw and plate, and the other end providing a spring cooperative to retain the pad on the holder.

3. A holder for a pad of checks including, in combination, a pad supporting plate having a punch opening, and a strip of resilient metal held on the plate intermediate its ends, the opposite ends of said strip lying opposite opposite faces of said plate respectively, one of said ends having a punching jaw adapted to cooperate with the punch opening to mark a check, and the other end providing a spring cooperative to retain the pad on the holder, said holder having a pointer outside the pad for indicating the position of the punching jaw.

4. A holder for a pad of checks including, in combination, a pad-supporting plate having a punch opening, said plate having a peep-opening at a point outside said pad, and a strip of resilient metal held on the plate intermediate its ends, the opposite ends of

said strip lying opposite opposite faces of the plate respectively, one of said ends having a punching jaw adapted to cooperate with the punch opening to mark a check positioned between the jaw and plate, and the other providing a spring cooperative to retain the pad on the holder, said holder having a pointer outside the pad for indicating the position of the punching jaw.

5 10 5. A holder for a pad of checks including, in combination, a pad-supporting plate having a punch opening, said plate having a peep-opening at a point outside said pad, and a strip of resilient metal held on the 15 plate intermediate its ends, the opposite ends

of said strip lying opposite opposite faces of the plate respectively, one of said ends having a punching jaw adapted to cooperate with the punch opening to mark a check positioned between the jaw and plate, and the other providing a spring cooperative to retain the pad on the holder, said holder having a pointer outside the pad for indicating the position of the punching jaw, and a 20 check arresting stop, whereby the numbers 25 on the check are displayed through the peep-opening when the check is in position to be punched.

In testimony whereof I affix my signature.
EDWARD KIRBY BOTTLE.
